UNITED STATES PATENT OFFICE

CHARLES H. CHASE, OF STONEHAM, MASSACHUSETTS, ASSIGNOR TO CARO CLOTH CORPORATION, OF CAROLINA, RHODE ISLAND, A CORPORATION OF DELAWARE

NEEDLING MACHINE

Application filed August 8, 1928. Serial No. 298,230.

My present invention relates to textile machinery and more particularly to an improved needling machine for needling textile fibres through and incorporating the same with a base fabric and with the fibres themselves.

In my copending application for needling machines, filed March 8, 1927, under Serial No. 173,767, I have described and claimed an improved needling machine wherein a plurality of banks of needles are arranged in groups and the groups adapted to be operated in any desired sequence or order. With such design I have been able to eliminate the excessive vibration inherent in machines of this type as constructed in the past and the absence of vibration enables me to speed up the machine to an appreciable extent, with the result that I am able to produce a more uniform product and at a higher rate of speed than has heretofore been possible.

In the practical application of the machine referred to, various improvements suggested themselves and in my present invention I have obviated the difficulties encountered in the practical application of my former machine. I have, however, retained the novel feature of arranging the banks of needles in groups and with the feature of having such banks of needles operable in any desired grouping or order. For simplicity of construction, however, I have arranged the drive shaft or crank shaft in my present machine in sections and with means to couple such sections together to form practically a unitary crank shaft. This has enabled me to more accurately adjust the throw of the cranks on the shaft during manufacture and has reduced the cost of producing the same to a considerable extent.

I have in my present machine produced a new needle rod, needle bar, as well as a needle guide, which differ materially from the equivalent elements as shown in my former application, and am enabled thereby to utilize a needle bar carrying a considerably greater number of needles than has formerly been considered possible and my present needle bar is more easily adjusted and broken

or bent needles more quickly and easily repaired or replaced.

Further, I have improved to a material degree the sliding frame carrying the needle bar structure and I consider this matter an important feature of my invention.

Various other improvements over my former machine have been made and the details of such will appear during the description of the construction and operation of the machine.

In the accompanying drawings illustrating a preferred embodiment of my invention,

Fig. 1 is a plan view;

Fig. 2 is a side elevation, partly in section; 65

Fig. 3 is a sectional elevation on the line 3—3 of Fig. 2;

Fig. 4 is a sectional elevation on the line 4—4 of Fig. 3;

Fig. 5 is a section on the line 5—5 of 70 Fig. 3;

Fig. 6 is a rear elevation of the right-hand end of Fig. 2;

Fig. 7 is a side elevation of a complete needling unit; 75

Fig. 8 is a sectional plan view on the line 8—8 of Fig. 7;

Fig. 9 is an end elevation of Fig. 7;

Fig. 10 is a sectional elevation on the line 10—10 of Fig. 7; 80

Fig. 11 is a sectional elevation on the line 11—11 of Fig. 7;

Fig. 12 is a plan view of a portion of a needling unit removed from the needle bar;

Fig. 13 is a perspective view of a needle 85 guide;

Fig. 14 is a perspective view of a portion of one of the needles employed;

Fig. 15 is a section through the coupling of the crank shaft elements, and 90

Fig. 16 is an elevation of a coupling showing the means for adjusting the counter shaft.

Referring to the drawings, 10 designates base bars on which are formed uprights 11, there being two uprights 11 for each base bar 95 10, each pair of uprights being spaced apart from each other, as clearly shown in Fig. 3, and are tied together at their tops by bars 12. These bars 12 are secured to the uprights 11 by bolts 13. The base bars 10 are adapt- 100

ably secured to a framework 14 in any manner, preferably by means of bolts 15. The base bars 10 are spaced apart from each other and are held in spaced relation by the bolts 15, engaging through the same into the frame 14, and also by means of a channel plate or bar 16. The bar 16 extends between the pairs of uprights 11 and is secured at its ends to the cross bars 12 in any convenient manner. 10 Mounted on top of the channel bar 16 at each end thereof are aligned bearings 17, such bearings being secured in position on the channel bars 16 and the channel bar being secured in position on the cross bars 12 by uprights 18. Also mounted on top of the channel bars 16 and intermediate the bearings 17 and in alignment therewith is a bearing 19. Rotatably mounted in the bearings 17 and 19 is a shaft 20. Secured to the shaft 20 at each end thereof is a crank arm 21 for a purpose to be hereinafter described.

The uprights 11 are spaced apart from each other, as above described, and the opposing faces are parallel to each other and constitute 25 vertically arranged spaced slides. In each pair of uprights there is slidably mounted a framework 27, such framework comprising substantially a U-shaped member, as viewed in Fig. 3. On the cross portion of the 30 U is secured one end of a cable 28, such cable extending upwardly to any desired point and with its upper end attached to one arm of a bell crank lever 29. The bell crank lever is pivotally mounted in any suitable manner and to the end of the other arm thereof is attached one end of a cable 30. This cable runs over a pulley 31 rotatably mounted on a shaft 32 at any convenient place, and to the end of the cable 30 is attached a counter- 35 balancing weight 33. It will be understood, of course, that there is one cable 28 with the associated mechanism as described for each of the U-shaped members 27 and, therefore, there is a weight 33 for each U-shaped member. 40 Secured to the inner faces of the arm of the U-shaped member 27, by bolts 34, is a substantially rectangular hollow member 35 which ties the U-shaped members 27 together with the member 35 into a substantially unitary element, which element is slid- 45 able on the ways formed on the inner face of the uprights 11. Secured to the upper face of the rectangular member 35, and at various points along the length thereof, are 50 bearings 36, which bearings are in alignment with each other and rotatably mounted therein is a multi-throw crank shaft 37. The crank shaft 37 is preferably made in a plurality of parts for ease and economy in 55 manufacture and in order that the various throws of the crank shaft may be more accurately machined. The method of attaching the various parts of the crank shaft together are illustrated in Fig. 15, where on 60 one element is formed a portion 38 internally

machined at 39 to receive a plug member 40 formed on a member 41 on the adjacent section. After the elements of the crank shaft 37 are positioned relatively to each other, the portions 38 and 40 have drilled therethrough a taper hole 42, in which is driven a taper plug 43 held against removal by a screw 44 that is threaded into both the element 38 and the taper plug 43. Along the end face of the rectangular member 35 and in vertical alignment with the various throws of the crank shaft 37 are secured, by bolts 44, cylindrical members 45 of suitable internal diameter and length. Slidably mounted in each of the cylindrical members 45 is a cylindrical crosshead 46 provided with a wrist pin 47, on which is rotatably mounted the lower end of a connecting rod 48. The upper end of the connecting rod 48 is pivotally attached to the throw of the crank shaft 37, with which throw the particular cylindrical member 45 is in alignment. The throws of the crank shaft 37 are arranged in pairs, that is, each two throws of the crank shaft beginning from either end, or as shown in Fig. 4 from the right-hand end, are parallel to each other so that during the rotation of the crank shaft, the first two throws thereof move in unison and occupy the same angular position with respect to each other. Therefore, the connecting rods 48 pivotally mounted thereon will move the cylindrical crossheads 46 associated therewith in a vertical direction so that the two cylindrical crossheads 46 will occupy a position in the same horizontal plane simultaneously. Pivotally attached to the wrist pins 47 of the cylindrical crossheads 46 and extending downwardly therefrom are members 49, such members being likewise arranged in pairs and each pair of members 49 being attached to the upper surface of a needle bar 50 by pins 51 or in any other suitable manner. The manner in which needles are carried by the needle bar 50 and the construction of such needles, as well as the detailed construction of the needle bar 50, will be described in detail hereinafter.

Secured to the multi-throw crank shaft 37, adjacent one end thereof, is a sprocket 52 which is in alignment with a sprocket 53 on the shaft 54, which shaft is rotatably mounted in bearings 55 secured to brackets 56 that are, in turn, secured to the rectangular member 35 by bolts 57. Over the sprockets 52 and 53 runs a sprocket chain 58 and by means of which power is transmitted from the multi-throw crank shaft 37 to the shaft 54. The sprocket 53 is secured to a face plate 59 that is loosely mounted on the shaft 54, and such face plate is adjustably attached to a second face plate 60 keyed to the shaft 54 by key 61. The face plate 60 is provided with accurate slots 62 through which pass bolts 63 that screw into the face plate 59. By means of the bolts 63 and arcuate slots 62, it is obvious

that the relative position of the sprocket 53 with relation to the shaft 54 may be varied within certain desired limits for a purpose to be hereinafter described. Keyed to the 5 shaft 54 at the end thereof remote from the sprocket 53 is a sprocket 64 that is in alinement with a sprocket 65 secured to a shaft 66, that is rotatably mounted in bearings 67 mounted on brackets 68, secured to the under 10 face of the rectangular member 35 by bolts 69. Over the sprocket wheels 64 and 65 runs an endless sprocket chain 70 and by means of which power is transmitted from the shaft 54 to the shaft 66. Formed on the shaft 66 15 are eccentrics 71, there being one such eccentric 71 for each of the members 49, and such eccentrics 71 are in alinement with the members 71. On each of the eccentrics 71 runs an eccentric strap 72 that has formed as a 20 part thereof a connecting rod 73, and the free end of such connecting rod 73 is pivotally attached at 74 to the member 49 and intermediate the ends of such member. The ratio of the sprockets constituting the 25 drive between the multi-throw crank shaft 37 and the shaft 66 is such that there is one complete oscillation of the connecting rod 73 for each complete revolution of the shaft 37, and the result is that the needle bar 50, as well 30 as the elements carried thereby, move in a closed path. It is in order to provide for adjustment to regulate the relation between the multi-throw crank shaft 37 and the needle bar 50 that the adjustable connection between 35 the shaft 54 and the sprocket 53 has been designed and which has been described above.

Secured to the multi-throw crank shaft 37, adjacent to one end thereof, is a sprocket 174 which is in alinement with a sprocket 75 40 secured to one end of a shaft 76 that is rotatably mounted in bearings 77 formed on a bracket 78 on one of the uprights 11. Over the sprockets 174 and 75 runs an endless sprocket chain 79 and by means of which 45 power is transmitted from the shaft 76 to the multi-throw crank shaft 37 and the method of connection between such shafts 76 and 37 permits a limited vertical movement of the multi-throw crank shaft 37 with respect to the shaft 76 without impairing the 50 efficiency of the connection. Secured to the shaft 76 adjacent to the end thereof remote from the sprocket 75 is a sprocket 80 which is connected in any suitable manner to a driving mechanism (not shown). Pivotaly connected to each of the cross members 27 on shaft 81 is the lower end of a connecting rod 82 and the upper end of this connecting rod is pivotally attached to the outer end of a 55 crank arm 83 secured to the shaft 20. Rotation of the shaft 20 in either direction, therefore, will cause either an upward or downward movement of the U-shaped members, of which 27 is a part, together with the rectangular member 35, with respect to the uprights

11; and the mechanism above described with respect to the U-shaped members 27, rectangular members 35, and all mechanism connected therewith will move as a unit under these conditions. The mechanism described 70 is counterbalanced by the weights 33 above referred to and, therefore, such mechanism is in balanced relation on the uprights 11.

The needle bars 50, which comprises an elongated member secured, as above described, to the lower ends of the members 49 and such needle bars are provided on their ends with plane surfaces so as to have each of the needle bars capable of being placed end to end with respect to each other and the plane surfaces will, therefore, act as bearings to insure proper alinement thereof. The under face of each of the needle bars 50 lies in a single plane and the body of such needle bar 50 at one end thereof extends downwardly, as indicated at 85, and forms a groove 86, which acts as a holding member for mechanism to be hereinafter described. Formed on the body of the needle bar 50 on the upper face thereof and on the side remote from the member 85 are spaced lugs 186, through each of which pass bearing bolts or shafts 87, such shafts 87 being in alinement with each other. 88 designates a clamping bar provided on its upper rear surface with a plurality of 90 spaced ears 89, such ears being arranged in pairs and each pair co-operating with the lugs 186 above referred to. The member 88, will, therefore, be pivotally attached on the shafts 87 and will be movable into and out 95 of operative position. On the lower front end of the member 88 is formed a member 90 and when the members are in the position shown in Figs. 9, 10, and 11, for example, the elements 85 and 90 will form with the 100 under surface of the body of the needle bar 50 practically a dove-tailed slot in which working elements may be positioned. The body of the needle bar 50, as well as the elements 85 thereof and the member 88, are 105 drilled at a plurality of points transversely of the body to receive, through bolts 91, the bolts 91 passing entirely through the body of the needle bar 50 and through the member 88. The outer free end of such bolts 91 are 110 threaded to receive clamping nuts 92 and by means of which the member 88 may be drawn into close engagement with any mechanism arranged in the dove-tailed slot above referred to and by means of which the mechanism is clamped securely in position.

The mechanism to be placed in the dove-tailed slot above referred to constitutes a needle bank assembly and is composed essentially of a central plate 93, the lower end of 125 which is reduced, as indicated at 94, and such reduced portion 94 is drilled at various points along its length to receive the screws 95. 96 designates needle plates provided with alternately arranged clearance holes 97 and 130

threaded holes 98 to facilitate their assembly on the portion 94 of the center plate 93. A screw 95 passes through one of the clearance holes 97 through the hole in the reduced portion 94 and enters the threaded hole 98 of the oppositely arranged needle plate 96. The outer faces of the grooved needle plates 96 are grooved to receive the shank 99 of needles 100 and also the top edge of such needle plates 96 are grooved to receive the upper bent shank portion 101 of such needles. 102 designates a member of the same length as the needle bar 50 and provided on its upper outer face with a projection 103 that fits in the groove 86 in the needle bar 50 and with a groove 105 that receives the lower projecting portion 85. This member 102 is threaded at various points along its length to receive screws 105. The member 102 is also drilled at various points along its length to receive screws 106, which screws thread into threaded holes in member 96 identical with the members 96 above described and which members 96 are grooved, as described, to receive the needles 100 in parallel relation. Associated with the member 102 and its associated member 96 is a member 107 constituting a needle spacing plate and provided with an angular cut-out portion that co-operates with the grooved side and grooved upper end of the member 96 and which is drilled to receive the screw 105 above referred to, and which screw 105 holds the member 107 firmly in position on the member 102, and this assembly 102, 96, 35 member 107, and group of parallelly arranged needles 100 constitutes a unitary needle group. 108 indicates a member provided at its upper outer end with a projection 109 adapted to engage in a groove formed by the member 88 and the body of the needle bar 50 and with a groove 110 adapted to receive the element 90 of such member 88. This member 108 is drilled at various points along its length to receive screws 106 for the purpose of securing to such member 108 grooved needle members 96. Associated with such members 108 is one of the members 107, screws 105 being utilized to hold such members together. The units composed of the members 102, 96, and 107 not only hold a bank of needles 100 rigidly in parallelly arranged position, but also each unit is associated with an element 96 on either side of the reduced portion 94 of the central plate 93 to hold in position in the serrations in the members 96 additional banks of parallelly arranged needles 100. To insure that these latter banks of needles 100 will be held permanently and rigidly in position, the elements 102, 107, 93, 50 107 and 108 are drilled transversely along their length, the perforations being in alignment with each other and one of the members, as 102, is drilled and tapped to receive the threaded end of bolts 109 that pass through the elements 108, 107, 93, 107 respectively and

in the order named. With the bolts 109 in position to hold the elements together, there is formed a unit carrying a plurality of rows of banks of parallelly arranged needles 100, the banks of needles 100 being arranged in staggered relation to each other, as clearly seen in Fig. 12.

The needle bar assembly is constructed and assembled as above described, and it will be noted that the upper edges or surfaces of the elements 102, 107, 93 and 108 are grooved to permit insertion or positioning of the bolts 91 when the needle bar assembly has its top surface in engagement with the bottom surface of the needle bar 50 and, therefore, these grooves act as means for positioning the needle bar assembly with correct relationship to the needle bar 50. It is, therefore, impossible to assemble the needle bar 50 and the needle bank assembly just described in any but the correct position. Further, such needle bank assembly is readily attached to or detached from the needle bar 50, and assuming that the needle bank assembly is in position on the needle bar 50 and that it is desired to remove the same for the purpose of repairing or replacing damaged or broken needles, then the operator will back off the nuts 92 from the bolts 91, will slide the bolts 91 rearwardly, or to the right, as viewed in Figs. 9, 10 and 11, and will swing the element 88 upward in a clockwise direction on the various shafts 97, when it will be possible to readily remove the needle bank assembly from association with the needle bar. By having extra needle bank assemblies a new one may be inserted in place of the old by merely reversing the above operation, or, of course the machine may be placed out of commission until the needle bank assembly has been properly repaired.

The operation of the improved construction is as follows, it being assumed that the device has been constructed and assembled as above described, and that it is desired to needle a web of fleece or other fibrous material onto a base fabric, which is indicated in dot and dash lines in the drawings, particularly Figs. 2, 4, 6, 7, 9, 10 and 11. Suitable means is provided for feeding the base fabric at the proper rate of speed commensurate with the distance between the various layers or banks of parallelly arranged needles 100 or with respect to the vertical oscillation thereof, and also the distance between the various layers or banks of parallelly arranged needles 100 is computed with this end in view. Power is thrown into the multi-throw crank shaft 37 by means of power transmitted to the sprocket 80 on the shaft 76 as above described, and this causes a rotative movement of the multi-throw crank shaft 37 and, therefore, a reciprocating movement of the cylindrical crossheads 46 in pairs and in any desired groups of pairs. As

shown for example in Fig. 2, the two outermost banks of needles 100 operate together and then afterwards, for example, the two middle banks of needles 100 operate together, and lastly, the second and fifth banks of needles operate together. By thus having but a portion of the groups of banks of needles 100 moving into operative position at any one time, vibration is reduced to a minimum and it is possible to noticeably increase the speed of operation.

Referring to Fig. 3, the construction is so arranged that as the member 49 carrying the banks of needles 100 moves downwardly and into and through the base fabric indicated by dot and dash lines in the drawings, the lower end of such member 49, together with the needle bar 50 and attached needles, is moved forwardly at the same rate of speed as that imparted to such base fabric and this forward movement continues as long as the bank of needles is in engagement with such base fabric, the mechanism of which the arm 48 forms a part then bringing the lower end of the arm 49 together with the attached needle bar 50 back into its initial position. There is thus imparted to the banks of needles 100 not only a reciprocating motion due to the reciprocatory motion of the cylindrical cross-heads 46 but also a forward and backward movement thereof, with the result that the points of such needles travel in a closed path. As the needles not only pierce and penetrate the base fabric, but also move along with such fabric, there is no tendency on the part of the needles 100 to tear the base fabric in any way or to injure the fibrous material of the fleece.

Having thus described my invention, what I claim as new is:

- 40 1. In an improved needling machine of the kind described, the combination of a central plate, a needle spacing plate thereon, a needle bank unit, and means for attaching said unit to said central plate.
- 45 2. In an improved needling machine of the kind described, the combination of a central plate, needle spacing plates attached to each side thereof, a needle bank unit arranged on each side thereof, and means for attaching said units to said central plate.
- 50 3. A unitary needle group comprising a central plate, a pair of needle plates each provided with a plurality of parallelly arranged grooves on one face, means for attaching said needle plates, one on each side of the central plate, needles arranged in each of the grooves formed in the plate, a holding member arranged one on each side of the central plate abutting against said central plate and against the needles arranged in the grooves in the needle plates, a second pair of needle plates each provided with a plurality of parallelly arranged grooves on one face, means for attaching said needle plates, one on each side of the central plate, needles arranged in each of

the grooves formed in the plate and abutting against the opposing face of the holding member, a pair of clamping members arranged one on the outer faces of the holding members and associated second pair of needle plates, 70 means for attaching the said second pair of needle plates to the clamping member, means for attaching the holding members to the clamping members, and means for attaching all said elements together into a unitary structure. 75

In testimony whereof, I have signed my name to this specification.

CHARLES H. CHASE.
